Filed Apr. 16, 1968, Ser. No. 11,476

Term of patent 14 years

Int. Cl. D22—02

U.S. Cl. D22—7

FIG. 1 is a side elevational view of my design for a base for a rifle telescopic mount shown attached to a rifle and supporting a telescopic sight indicated in broken lines; and

FIG. 2 is an enlarged fragmentary view of FIG. 1;

FIG. 3 is an enlarged perspective view of the base as shown in FIGS. 1 and 2; and

FIG. 4 is a sectional view taken on the line 4—4 of FIG. 3.

The broken lines are shown for illustrative purposes only.

I claim:

The ornamental design for a base for a rifle telescopic mount, substantially as shown and described.
